C. S. FRANKLIN.
RECEIVER FOR WIRELESS SIGNALS.
APPLICATION FILED FEB. 26, 1919.

Patented Apr. 22, 1919.

UNITED STATES PATENT OFFICE.

CHARLES SAMUEL FRANKLIN, OF LONDON, ENGLAND, ASSIGNOR TO MARCONI WIRELESS TELEGRAPH COMPANY OF AMERICA, OF NEW YORK, N. Y., A CORPORATION OF NEW JERSEY.

RECEIVER FOR WIRELESS SIGNALS.

1,301,246.

Specification of Letters Patent. Patented Apr. 22, 1919.

Application filed February 26, 1919. Serial No. 279,396.

To all whom it may concern:

Be it known that I, CHARLES SAMUEL FRANKLIN, a subject of the King of Great Britain, residing at Marconi House, Strand, 5 London, England, have invented new and useful Improvements in Receivers for Wireless Signals, of which the following is a specification.

In receivers based on the interference principle it is usual to employ a local oscillator which can be so adjusted as to produce oscillations differing in frequency by a desired amount from the oscillations produced in the receiver by the incoming waves. 15 In some well known receivers the receiving device is its own local oscillator.

The result is that during reception there are in the receiving circuits two sets of oscillations which interact with each other, producing a compound oscillation of varying amplitude.

The receiver usually rectifies this compound oscillation into a uni-directional current of varying strength and so produces in the receiving telephone a note which has a frequency equal to the difference of the frequencies of the received and local oscillations, and which can therefore be adjusted by varying the frequency of the local oscillations.

The constancy of the note depends upon the constancy of the frequency of the received and local oscillations. For frequencies below about 1,000,000 per second (300 meter waves) it is not difficult to maintain a sufficiently constant frequency; for frequencies about 3,000,000 it is still practicable though not easy to maintain a sufficiently constant frequency; for frequencies about 40 30,000,000 it is practically impossible to maintain the frequency sufficiently constant.

Assuming 30,000,000 to be the frequency received, then the local oscillator must give a frequency of 30,001,000 or 29,999,000, in order to give an interference note of 1,000. Should either frequency vary one hundredth of one per cent. the interference note may change from 1,000 to 4,000. Practically when working with frequencies of this order the interference note varies so rapidly and to such an extent with the small variations of frequency which take place that the signals are unreadable.

According to this invention, the frequency of the local oscillations is varied by a small percentage, regularly and in a continuous manner. This may be done by arranging in the local generator a condenser which consists partly of segments arranged on a rotating disk or cylinder, so that the capacity varies continually between two limits.

A receiver constructed according to this invention works as follows:

Assume the received frequency to be 30,000,000 and the local generator arranged to give a 30,000,000 frequency with variations of a half per cent. above and below this 1,000 times per second. During reception an interference note is produced which varies from zero to a frequency of 150,000. An audible sound is produced in the telephone only during the time that the interference note is varying through the range from about 8,000 to zero and back to 8,000; that is to say, while the interference note is within 75 audible limits. The period occupied by this range is so short that only a "click" occurs in the telephone for every variation between the above limits of the frequency of the local oscillator. As, however, this variation occurs 1,000 times per second, a clear note having a frequency of 1,000 per second is heard whenever signals are received.

A receiver for short waves is thus obtained which has the great sensitiveness of 85 the interference receiver, but is independent of very small variations in frequency either in the received waves or in the local oscillator.

The invention is illustrated by the accompanying diagram, in which A is an aerial in series with two coils N, R, the latter coupled to the receiver S. Coupled to the coil N is a coil L in series with a condenser C in parallel with which latter is a variable condenser formed of two strips *a*, *a*, and segments *b*, *b*, carried upon a disk or cylinder which can be rapidly rotated. The capacity of the circuit L C *a* *a* depends upon the position of one of the segments *b* relative to the strips *a* *a* and varies between a maximum and minimum as the segments *b* pass the strips.

Across the coil L is connected a thermionic device *d* in series with a battery B so arranged as to produce high frequency oscil-

lations in the circuit $L C \alpha \alpha$ in a manner now well understood.

What I claim is:—

1. In an interference receiving apparatus for wireless signals, a circuit containing a generator of local oscillations, and means whereby the frequency of said local oscillations is caused to vary regularly and in a continuous manner.
- 10 2. In an interference receiving apparatus for wireless signals, an antenna, a circuit associated therewith containing a generator of local oscillations, and means for regularly and in a continuous manner increasing the frequency of the local oscillations above and decreasing them below the frequency of the received oscillations.
- 20 3. In a wireless telegraph receiver, the combination of an aerial, an oscillatory circuit coupled thereto, local means for generating in said circuit high frequency oscillations, and means for varying regularly and continuously the time period of said circuit.
- 25 4. In a wireless telegraph receiver, the combination of an aerial, an oscillatory circuit coupled thereto, local means for generating oscillations in said circuit, and means for varying regularly and continuously the frequency of such oscillations.
- 30 5. In a wireless telegraph receiver, the combination of an aerial, an oscillatory circuit coupled thereto, local means for generating in said circuit high frequency oscillations, and means for varying regularly 35 and continuously the capacity of said circuit.
- 40 6. In an interference receiving apparatus for wireless signals, an antenna, a local circuit associated therewith containing a generator of oscillations, and means for regularly and continuously varying the frequency of the local oscillations above and below the limiting frequencies at which the beats produced by reaction of the received 45 and local oscillations are audible, said means being so constructed that the frequency of said beats passes through the audible range so frequently as to produce a distinct note in the receiver corresponding to the group 50 frequency of the audible beats.

CHARLES SAMUEL FRANKLIN.
